UNITED STATES PATENT OFFICE.

CHRISTOPHER H. OLSON, OF DECATUR, ILLINOIS.

COFFIN..

SPECIFICATION forming part of Letters Patent No. 255,112, dated March 21, 1882.

Application filed January 3, 1882. (No model.)

To all whom it may concern:

Be it known that I, CHRISTOPHER H. OLSON, a citizen of the United States, residing at Decatur, in the county of Macon and State of Illinois, have invented certain new and useful Improvements in Coffins, of which the following is a specification, and which has never been patented to me, nor to others with my knowledge and consent, in any foreign country.

10. In the drawings accompanying and forming a part of this specification, Figure 1 shows a plan of a coffin-lid embodying my invention. Fig. 2 is a side elevation of the same. Fig. 3 is a plan, and Fig. 4 a transverse section, of the connecting device.

15. Similar letters of reference indicate the same parts in all the figures.

A is the coffin-lid, B the swinging plate, and C the portion of the connecting device which is connected to the coffin-lid. C² is the portion of the connecting device attached to the face-plate by the plate c.

The connecting device is shown in detail in Figs. 3 and 4, in which a is a plate attached to

the coffin-lid, and provided with the circular 25 inclined plane b and annular elevation a'. c is a plate attached to the swinging plate, and provided with a hinge-extension that connects with shaft d and a foot-piece, c', that rests in a recess in plate a when the swinging plate is 30 down, and moves on plane b when the same is being elevated.

In operation the plate B is raised sufficiently to allow foot c' to clear the recess in a and swung around, as shown in Fig. 2.

I claim—

In a two-part coupling for the lid and face-plate of a coffin, the part C, having annular flange a, annular elevation b, with low portion in front and high portion in the rear, and made 40 hollow to receive the shaft d, to which is pivoted the part C², carrying the foot c', and the part c, attached to the face-plate, as set forth.

CHRISTOPHER H. OLSON.

Attest:

OLIVER Z. GREENE,
THOMAS T. ROBERTS.
